UNITED STATES PATENT OFFICE.

ANTHONY C. VANADIA, OF FLINT, MICHIGAN.

FIRE-ALARM BOX.

1,218,230.

Specification of Letters Patent.

Patented Mar. 6, 1917.

Application filed August 11, 1916. Serial No. 114,322.

To all whom it may concern:

Be it known that I, ANTHONY C. VANADIA, a citizen of the United States, residing at Flint, county of Genesee, State of Michigan, have invented a certain new and useful Improvement in Fire-Alarm Boxes, and declare the following to be a full, clear, and exact description of the same, such as will enable others skilled in the art to which it pertains to make and use the same, reference being had to the accompanying drawings, which form a part of this specification.

This invention relates to means for requiring the attendance until the arrival of the department of one who pulls the fire-alarm box. It consists of an improvement over prior handcuff devices intended to trap one's hand within the box when he pulls the same.

20 In the drawings,—

Figure 1 is an elevation of the inside of the fire-alarm box door, showing the handcuff device and its operating parts.

25 Fig. 2 is a similar view showing the same elements after the box has been pulled and the trap released.

Fig. 3 indicates how the hand of the one who pulls the box is trapped in the same. *a* indicates the door of the fire-alarm box; *b* a slot therein through which the one who desires to send the alarm must reach in order to pull the box. In pulling the box a latch *c* is retracted, by any suitable means (such means being old in the art it is not hereby detailed), allowing the yoke or handcuff *d* to let go under the influence of the powerful *U* spring *e*. In its reciprocation the yoke is guided between the angle bars *g* provided with lips *h* which serve to guide the same. One side of the yoke is notched

to provide ratchet teeth *i* over which may ride the spring detent *j* attached to the lower angle bar *g*. This detent prevents return movement of the yoke so that when the same is sprung upon the wrist of the puller of the box, the detent prevents the yoke being drawn back so as to enlarge the opening to allow the escape of the wrist.

From the above description it is apparent that I have improved over prior devices of this character by reason of the simplicity, effectiveness and cheapness of the device exhibited to accomplish the desired result.

What I claim is:

1. In a fire-alarm box, the combination with a closure provided with a slot, a pair of angle bars on opposite sides of the slot, a yoke guided by the angle bars and provided with ratchet-teeth in one arm, a spring detent secured to one of the angle bars and engaging the ratchet-teeth, a latch for holding the yoke retracted, and a spring for throwing the yoke partially across the slot where it is locked by the spring detent.

2. In a fire-alarm box, the combination with a closure provided with a slot, a pair of bars on opposite sides of the slot, and provided with lips, a yoke guided by the bars and lips and provided with ratchet-teeth in one arm, a spring detent engaging said ratchet teeth, a hook on one end of the yoke, a latch for engaging said hook and holding the yoke retracted and a *U* spring normally contracted and exerting a pull on the opposite end of the yoke to throw it across the slot when the latch is released where it is locked by the spring detent.

In testimony whereof, I sign this specification.

ANTHONY C. VANADIA.
